(57) **CLAIM**

We claim the ornamental design for a light tube assembly, as shown and described.

DESCRIPTION

FIG. 1 is a side, and perspective view of first side of one embodiment of a light tube assembly, the first side having a lens of the light tube assembly shown without broken lines; FIG. 2 is a side, end perspective view of the first side of the light tube assembly of

FIG. 1 with one end cap removed to more clearly illustrate the contours of the outer surfaces;

FIG. 3 is a side, end perspective view of a second side of the light tube assembly of FIG. 1;

FIG. 4 is a side, end perspective view of the second side of the light tube assembly of FIG. 1 with one end cap removed to more clearly illustrate the contours of the outer surfaces;

FIG. 5 is an elevation view of one end of the light tube assembly of FIG. 1 with the end caps removed to more clearly illustrate the contours of the outer surface, with the lens of the

light tube assembly shown at the top of the illustration;

FIG. 6 is an elevation view of one end of the light tube assembly of FIG. 1, the second end is the same as the first end;

FIG. 7 is a reduced scale elevational view of a third side of the light tube assembly of FIG. 1, the fourth side of the light tube assembly is the same as the third side;

FIG. 8 is an enlarged, elevational, partial view of the third side of the light tube assembly of FIG. 1;

FIG. 9 is a reduced scale elevational view of the first side of the light tube assembly of FIG. 1;

FIG. 10 is an enlarged, elevational, partial view of the first side of the light tube assembly of FIG. 1;

FIG. 11 is a reduced scale elevational view of the second side of the light tube assembly of FIG. 1; and,

FIG. 12 is an enlarged, elevational, partial view of the second side of the light tube assembly of FIG. 1.

The broken lines showing light sources, interior features and pin connectors illustrate the environmental structure of the light tube assembly and form no part of the claimed design.
